COMBINED COLANDER, STRAINER, AND STEAMER.

1,134,837.

Specification of Letters Patent.

Patented Apr. 6, 1915.

Application filed June 2, 1914. Serial No. 842,461.

To all whom it may concern:

Be it known that I, MAC L. Fox, a citizen of the United States, residing at Columbiaville, in the county of Lapeer and State of Michigan, have invented new and useful Improvements in Combined Colanders, Strainers, and Steamers, of which the following is a specification.

This invention relates to a combined colander, strainer and steamer; and it has for its object the provision of a device of this character which will be provided with a funnel-like body portion having relatively separable sections between which a foraminated disk may be properly interposed and removably fitted thereto in such manner that it may be quickly disconnected therefrom and sterilized and maintained in a sanitary condition.

Another object of the invention is the provision of a device of this character which may be readily converted from a strainer to a steaming device and which when converted into the latter will be of such form that the steam will be made to freely circulate through that portion of the device in which the articles to be cooked are arranged.

With these and other objects in view, the invention consists of certain novel features of construction, combination and arrangement of parts, as will be hereinafter described and claimed.

In the accompanying drawings:—Figure 1 is a perspective view of the device; Fig. 2 is a vertical section therethrough; Fig. 3 is a perspective view of the male section of the device; and Fig. 4 is a perspective view, showing the different forms of foraminated disks.

The device consists of a female section 1 and a male section 2, the former being provided with a substantially funnel-shaped upper portion 3, whose walls terminate into a relatively broad seat 4 at the juncture of the upper end of the section 1 with the base of the portion 3, as clearly shown in Fig. 2. The female section 1 is provided immediately beneath the seat 4 with a circular series of corrugations 5, and below the corrugations the section 1 is provided with an integral section 6. The male section 2 is provided with an external thread 7, and at a point above the thread said male section 55 is provided with an annular series of cor-

rugations 8 and a flange 9, the latter being disposed at an angle greater than a right angle to the vertical of the section 2, and it is split, as at 10, so that it is free to yield for a purpose to be hereinafter referred to.

I propose to construct the device so that it may be used for the purpose of steaming articles of food, for use as a strainer or for use as a colander, and I, therefore, desire to employ a series of disks 11, 12 and 13, as shown in Fig. 1. These disks are of foraminated nature, and the meshes of the different disks vary according to the character of the work to be performed. That is to say the disk 11 has relatively fine meshes, and this disk may be used when the device is converted into a strainer. The disk 12 has slightly larger meshes and the same is thereby intended to be employed in connection with the device when the latter is converted into a colander. The disk 13 has still coarser meshes, and it is therefore designed to be used in connection with the device when the latter is converted into a steamer. The disks 11, 12 and 13 are each of the same diameter, and either one of the said disks may be freely passed into the female section 1 of the device and they may be brought to bear against the seat 4 and it may be confined thereagainst by adjusting the section 2 in the member 1 and causing the flange 9 of said section 2 to bear against the disk and thereby securely confine the same therein at the bottom of the funnel portion 2. It is stated that the flange 9 is split at 10 to render the flange yieldable. This is preferred in order that the two flanges 9 and 4 may be properly relied upon to effect a proper seating of the foraminated disk. This construction is also preferred in that the corrugations 8 of the section 2 are free to slightly interlock with the similar corrugations 5 of the section 1. Incident to this arrangement the two sections 1 and 2 will be held against casual separation, as will be understood.

It is believed that a proper understanding as to the use of the device for straining purposes or at such time when the device is converted into a colander will be readily understood but in order that one may clearly understand the working of the device when converted into a steamer as hereinbefore described, it is said that when using the device in this manner the lower end of the device, or in other words the section 2 is ex-

- tended into a suitable utensil A. The foods to be cooked may be placed in the portion 3 above the foraminated disk of the device and it will thus be seen that the steam rising from the water will pass through the foraminated disk and it will enter the portion 3 of the device and freely circulate around the foods as will be readily understood.
- 5 In order that the steam will be held against escaping from the steaming portion 3 during the steaming operation it is preferred to provide a cover 14 hinged at 15 to one side of the portion 3. This cover is 10 provided with a spring clasp 16 which is adapted to engage in a keeper forming recess 17 formed exteriorly of the member 3. When the cover is adjusted to a closed position, the broad upper end of the member 15 20 25 3 is entirely closed and the steam will be properly confined within the member, as will be understood. The portion 3 is described as being substantially of funnel shape but it may be more correctly described as semi-spherical, the walls of which being bulged outwardly and upwardly and in effect the said portion 3 forms a closure for the utensil A to prevent the steam from escaping from the closure during the steaming 30 operation. The peculiar curvature of the
- portion 3 is also designed to permit the device to readily accommodate itself to utensils of different internal diameters. At diametrically opposite points upon the portion 3 are handles 17^a, 17^a which are the means 35 by which the device may be readily lifted from place to place or manipulated.

I claim:

The herein described combined colander, strainer and steamer comprising a vessel 40 having an opening in its bottom, a collar depending from its lower side and concentric with said opening and also having an inwardly extending annular flange around said openings, in combination with a tubular member open at its ends and threaded in said collar and provided at its upper end with an inwardly extending annular flange, and a foraminous disk secured between the flanges of said vessel and said tubular member, the said tubular member being made of resilient material and being provided with a slot extending across its screw threads and also across its flange.

In testimony whereof I affix my signature 50 in presence of two witnesses.

MAC L. FOX.
